Attorney.

UNITED STATES PATENT OFFICE.

HARRY D. LATHROP, OF CHICAGO, ILLINOIS.

CAN-WASHING MACHINE.

Application filed August 25, 1919, Serial No. 312,828. Renewed June 26, 1922. Serial No. 570,938.

To all whom it may concern:

Be it known that I, HARRY D. LATHROP, a citizen of the United States, and a resident of the city of Chicago, county of Cook, and 5 State of Illinois, have invented certain new and useful Improvements in Can-Washing Machines, of which the following is a specification.

My invention relates to improvements in 10 can washing machines, and more especially to means therein for guiding cans thereto, the object of the invention being to provide a simple and effective means for guiding cans through the machine which is adapted 15 to accommodate cans of different sizes.

Other objects will appear hereinafter.

The invention consists in the combinations and arrangements of parts hereinafter described and claimed.

20 The invention will be best understood by reference to the accompanying drawings forming a part of this specification, and in which,

Fig. 1 is a transverse vertical section of a 25 can washing machine embodying the invention.

Fig. 2 is a partial horizontal section of the same.

The preferred form of construction, as 30 illustrated in the drawings, comprises a can washing machine having longitudinal supporting rails 3 positioned therein and adapted to support the cans 4 in inverted positions, as they are fed through the machine and subjected to the different washing operations in any usual or desired manner. Cooperating with the supporting rails 3 are 35 two lateral guides 5 in the form of longitudinal angle irons positioned with one of 40 their legs extending horizontally and inwardly at a position somewhat above the level of the supporting surfaces of the rails 3. These angle iron guides 5 are rigidly secured to the inner ends of bolts 6 which pass 45 freely through openings in the uprights 7 of the frame of the machine and are adjustably secured thereto by means of clamping nuts 8 arranged on opposite sides of said up-

rights. By this arrangement, it will be observed that the guides 5 may be adjusted to 50 contact with the narrowed neck portions of the cans, thus securely guiding said cans along the supporting rails 3 and preventing tipping over of said cans. By means of the bolts 6 and nuts 8 the lateral positions of 55 the guides 5 may be adjusted as desired, to accommodate cans of different sizes.

While I have illustrated and described the preferred form of construction for carrying my invention into effect, this is capable of 60 variation and modification without departing from the spirit of the invention. I, therefore, do not wish to be limited to the precise details of the construction set forth, but desire to avail myself of such variations and 65 modifications as come within the scope of the appended claims.

Having described my invention, what I claim as new and desire to secure by Letters Patent, is:—

1. In a can washing machine, a support 70 adapted and arranged to guide inverted cans therethrough; laterally adjustable guides positioned above said supports on opposite sides of the path of said cans and arranged to embrace the neck portions of the cans; and adjusting bolts rigidly secured to said guides and adjustably secured to the frame of said machine, substantially as described.

2. In a can washing machine, a can support adapted and arranged for guiding inverted cans therethrough; laterally adjustable angle iron guides positioned above said support on opposite sides of the path of said cans and arranged to embrace the neck portions of said cans; and adjusting bolts rigidly secured to said guides and adjustably secured to the frame of said machine, substantially as described.

In testimony whereof I have signed my 90 name to this specification in the presence of two subscribing witnesses.

HARRY D. LATHROP.
